UNITED STATES PATENT OFFICE.

CHARLES W. SMITH, OF NORWALK, OHIO.

DESIGN FOR A CURTAIN-POLE BRACKET.

SPECIFICATION forming part of Design No. 24,106, dated March 12, 1895.

Application filed February 9, 1895. Serial No. 537,831. Term of patent 7 years.

To all whom it may concern:

Be it known that I, CHARLES W. SMITH, a citizen of the United States, residing at Norwalk, in the county of Huron and State of Ohio, have invented a certain new and useful Design for Curtain-Pole Brackets; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 Figure 1 is a side elevation of a curtain pole bracket embodying my design. Fig. 2 is a cross section on the line x, x of Fig. 1.

My design has reference to brackets for curtain poles, the special features of the design

20 being an annular pole supporting portion A having a central perforated opening a, the sides of the said annular portion being flat and parallel, and having a circumferential bead C, and a recess D each side of said bead.

E is a cylindrical portion flattened at F and 25 having a central circumferential bead G, the flaring conical outwardly extending surfaces H having contact at two points h , and h , with the portion A, the greatest diameter of the said conical portion terminating in a ridge I 30 on each side of the central bead, the outwardly extended convex portions J, the bead K having convex surfaces which adjoin inwardly turned convex-surfaces L, the bases of which terminate in ridges from which outwardly extend the concave surfaces M, the 35 apexes of which terminate in the spherical ends O.

What I claim is—

The design for a curtain pole bracket as 40 herein shown and described.

In testimony whereof I affix my signature in presence of two witnesses.

CHARLES W. SMITH.
